UNITED STATES PATENT OFFICE.

THOMAS E. BARROW, OF MANSFIELD, OHIO.

GRAVE-MARKER AND BOUQUET AND FLAG HOLDER.

SPECIFICATION forming part of Letters Patent No. 443,741, dated December 30, 1890.

Application filed May 27, 1890. Serial No. 353,291. (No model.)

To all whom it may concern:

Be it known that I, THOMAS E. BARROW, a citizen of the United States of America, residing at Mansfield, in the county of Richland and State of Ohio, have invented certain new and useful Improvements in Grave-Markers and Bouquet and Flag Holders, of which the following is a specification, reference being had therein to the accompanying drawings.

10 This invention relates to improvements in what may be termed a "grave-marker," "flag-securer," and "bouquet-holder," which is especially adapted to be placed upon the grave of soldiers to indicate the grave and serve as 15 an ornament therefor.

The object of the invention is the provision of a device of this character which will be efficient for the desired purpose, which can be produced at a low figure, and which will 20 present an ornamental and attractive appearance.

The invention consists of the device illustrated, described, and specifically claimed, and in the drawings accompanying this description—

25 Figure 1 represents an elevation of the device as it appears when in use, and Fig. 2 represents a vertical section of the device.

The device consists of the cup or urn A,

which may be of any shape or pattern and 30 decorated or ornamented in any desired manner, provided with a lug C, having an opening to receive the staff of a flag, and the interiorly-threaded sleeve H, in which engages the upper end of the tube B for securing the 35 device in place, and in the urn I have shown a bouquet G.

It will thus be seen that I provide a device which will mark the graves and present an ornamental and attractive appearance, which 40 will hold a bouquet and keep the flowers fresh by placing water in the urn, and which will be inexpensive.

I claim as my invention—

The herein-described grave-marker and flag 45 and bouquet holder, consisting of the urn having the lug projecting from the upper edge thereof and perforated to receive a flag-staff, the depending interiorly-threaded sleeve, and the tube having its upper end screwed into 50 said sleeve and forming a support and conduit for the urn.

In testimony whereof I affix my signature in presence of two witnesses.

THOMAS E. BARROW.
